UNITED STATES PATENT OFFICE.

NEHEMIAH MORTIMER THOMAS, OF PYMBLE, NEAR SYDNEY, NEW SOUTH WALES, AND
CUTHBERT GEORGE PETREE, OF BUNDABERG, QUEENSLAND, AUSTRALIA.

PROCESS OF MANUFACTURING CANE-SUGAR.

1,266,882.

Specification of Letters Patent. Patented May 21, 1918.

Application filed January 14, 1918. Serial No. 211,703.

To all whom it may concern:

Be it known that NEHEMIAH MORTIMER THOMAS and CUTHBERT GEORGE PETREE, subjects of the King of Great Britain and Ireland, residing, respectively, at "Loma Lagi," Roseville avenue, Pymble, near Sydney, New South Wales, Australia, and Bundaberg, Queensland, Australia, have invented new and useful Improvements in the Process of 10 Manufacturing Cane-Sugar, of which the following is a specification.

According to usual present practice, the raw juice obtained in the milling of sugar cane is defecated by the addition of lime and 15 the application of heat. In this treatment a heavy precipitate of scum and mud, hereinafter called "mud," is produced, and collected by settling and decantation. The mud is pumped into filter presses and the filtrate 20 is returned to the raw juice or is added to clarified juice drawn from the settling vessels. In some instances the whole of the juice after defecation is passed through filter presses.

25 Extraction of sugar charged liquids from defecation mud by filter pressing or by treating it in centrifugal machines is subject to the disadvantage that costly apparatus involving considerable labor cost for its operation is necessary.

It has been proposed to extract the sugar charged liquid from the mud by returning the mud to the milling circuit at a point therein subsequent to the initial shredding 30 or crushing, with the object that the sugar charged liquid it contains will be expressed by subsequent crushing and its solid elements retained in the megass. It is not ultimately profitable to return to the milling circuit the defecation mud produced from rich juice or 35 from mixed rich and thin juices obtained respectively in the early stage or stages of the crushing, because the liquid contained in the mud so produced is richer in sugar than is the liquid content of the macerated megass which enters the rolls at the stage of crushing following next after the application of the mud to the megass.

40 A satisfactory efficiency of extraction of sugar from the cane is attainable only when the megass in process of crushing is subjected to progressive maceration, and for this purpose the sugar content in the expressible liquids must progressively diminish. The 45 usual method when more than two stages of

crushing are employed is to return the thin juice from the final stage or stages of the crushing to the megass after it leaves the early stage or stages of the crushing and to apply maceration water to the megass prior 60 to the final stage or stages.

Our invention has for its object to provide a means whereby the sugar charged liquid may be extracted from the defecation mud by distributing such mud on the megass in the 65 milling circuit, without the addition of plant which is costly to operate, and without the disadvantage of requiring increase in the volume of maceration water otherwise necessary for reducing the residual sugar in the 70 final megass to a practical minimum, and without detriment to the efficiency of the extraction of sugar from the cane.

Our invention consists in distributing 75 upon the megass in the milling circuit a specially prepared defecation mud. This special preparation of the mud is effected by mixing mud produced from defecation of rich juice with raw thin juice obtained in a later stage or stages of multiple crushing 80 and submitting the mixture to defecation and settling thence without increasing the quantity of maceration water otherwise necessary, obtaining a mud the liquid element of which is less rich in sugar than is 85 the liquid content of the macerated megass which enters the rolls at the stage of crushing following next after the said distribution of such mud on the megass.

We may proceed in either of two ways, 90 which are identical in principle and object. In the first case we add the mud produced from defecation of the rich juice (i. e., the natural juice obtained in the first stage or stages of the crushing) to the raw thin juice 95 obtained in a later stage or stages of crushing, and we mix the clarified juice from the thin juice defecation with the rich juice, before the latter is defecated, taking the clarified juice from the defecation of the mixture 100 of rich juice and clarified thin juice direct to the evaporating plant. After the process is established in operation this mud obtained from the defecation of so-called rich juice is in fact mud obtained from the defecation 105 of a mixture of raw rich juice and the previously defecated clarified thin juice. In the second case we may omit the step of mixing the clarified thin juice with the raw rich juice, and instead thereof carry the clarified 110

thin juice direct to the evaporating plant separately or in conjunction with the clarified rich juice. In either case the sugar content in the liquid element of the mud is reduced below the sugar content in the liquid contained in the macerated first megass entering the second mill, so that it can be safely introduced into the milling circuit after the first crushing.

10 The process will suffer appropriate adaptation in each case, having regard to the mill plant in which it is installed, according to current principles of sugar mill operation. In a three mill crushing plant, for 15 instance, the specially prepared defecation mud and the raw juice from the third mill, separately or admixed, would be applied to the megass after it leaves the first mill, and the megass after leaving the second mill 20 would be macerated with water.

Our first method is diagrammatically illustrated for a three mill crushing plant in Figure 1 of the accompanying drawing; and our modified method for a similar plant is 25 similarly illustrated in Fig. 2 of the accompanying drawing.

In both figures the same reference letters indicate corresponding parts. The juice circuits are shown by full lines and the mud 30 circuits by dotted lines.

In Fig. 1, A is the first mill, B the second mill, and C the third mill. The rich juice from the mill A is screened at D, collected and limed in the tank E, and transferred 35 by pump F through the heater G to the settling vessel H. The clarified juice from the settling vessel H passes to the evaporating plant by the pipe line J and the mud passes by the pipe line or launder K to the tank L which receives the screened thin juice from the mill B, via the screen M. The mud and the thin juice are limed and transferred 40 by the pump N from the tank L to the heater O and thence to the settling vessel P. The clarified juice from the settling vessel P goes by the pipe line Q to the tank E, where it mixes with the rich juice and the mixture 45 is defecated. The mud from the settling vessel P goes by the pipe line or launder R to the megass between the mill A and the mill B. Maceration water is applied to the megass between the mill B and the mill C, and the thin juice from the mill C may be applied either with the mud from the settling 50 vessel P, or separately, to the megass.

In Fig. 2 the only difference from the process above described is that the clarified juice from the settling vessel P goes direct to the evaporating plant by the pipe line S, instead of being brought to the tank E.

Obviously the introduction into the milling circuit of mud containing in its liquid element a higher percentage of sugar than is carried by the liquid in the macerated megass entering the rolls at the stage of crush-

ing following such introduction of mud militates against the successful operation of the milling process, and either increases the quantity of the sugar lost in the final megass or renders necessary the addition of an otherwise unnecessary quantity of water to reduce to a reasonable margin of loss the quantity of sugar which remains in the final megass, thereby entailing additional cost for evaporating the superadded water.

It is not practicable to add the defecation mud to the shredded cane before the first crushing, as the shredded cane is at that stage heavily charged with juice and is not capable of absorbing any substantial quantity of additional liquid or of effectively retaining the solid elements of the mud.

What we claim as our invention and desire to secure by Letters Patent is:—

1. In a process for extracting sugar cane juice by successively crushing and macerating sugar cane, defecating the extracted products, and returning the defecation mud to the milling circuit, producing a specially prepared defecation mud for the said purpose by first mixing thin juice with mud obtained from defecation of richer juice and defecating the mixture whereby a mud is produced the liquid element of which is lower in sugar content than is the liquid element in the macerated megass with which such mud is incorporated and crushed.

2. In a process for extracting sugar cane juice by successively crushing and macerating sugar cane, defecating the extracted substances and returning the defecation mud to the milling circuit, reducing the sugar content of the liquid element in the defecation mud below the sugar content of the liquid element in the macerated megass which enters the rolls at the stage of crushing following next after the point in the milling circuit at which said mud is returned to said circuit by attenuating said mud and defecating the attenuated mixture to produce a clarified juice and a mud having a liquid element of reduced sugar content.

3. In a process for extracting sugar cane juice by successively crushing and macerating sugar cane, wherein defecation mud is returned to the milling circuit for the extraction of sugar charged liquid therefrom and for the retention of the solid elements of said mud with the megass, mixing mud obtained from defecation of relatively rich juice or juices extracted in the first stage or stages of the crushing, with raw thin juice extracted in the later stage or stages of the crushing and defecating this mixture of mud and raw thin juice to procure thereby a final mud the liquid element of which is lower in sugar content than is the liquid element of the macerated megass which enters the rolls at the stage of crushing following next after the point in the milling cir-

cuit at which said mud is returned to said circuit.

4. The herein described improvement in the extraction of sugar cane juice which consists in submitting the cane to a succession of crushings with intermediate maceration of the megass, defecating and settling the thin juice obtained in the late stage or stages of the crushing, admixing the clarified juice from said thin juice with rich juice obtained in the early stage or stages of the crushing, defecating such mixed juice separately from said thin juice, admixing the defecation mud from the said mixed juice which is rich in sugar content with said thin juice prior to defecation of said thin juice and distributing the mud which is obtained from the defecation of such mixture of mud and thin juice upon the megass at a point in the milling circuit where the liquid element of said mud is lower in sugar content than is the liquid element of the macerated megass which enters the rolls at the stage of crushing following next after the point in the milling circuit at which said mud is distributed on the megass.

5. In a process for extracting sugar cane juice by successively crushing and macerating sugar cane, and defecating the extracted products and returning the defecation mud to the milling circuit, reducing the sugar content of the liquid element of the mud prior to returning it to the milling circuit below the sugar content of the liquid element of the megass which enters the rolls at the stage of crushing following next after the point in the milling circuit at which said mud is returned by reducing the sugar con-

tent of the raw rich juice by admixing clarified thin juice therewith, thus reducing the sugar content of the defecation mud obtained from said rich juice and admixing the thus attenuated mud with raw thin juice and defecating the mixture of said attenuated mud and raw thin juice for the production of said clarified thin juice and of a still further attenuated mud for returning to the milling circuit.

6. The herein described improvement in the extraction of sugar cane juice, which consists in crushing the cane in a plurality of stages with intermediate maceration of the megass, defecating the rich juice obtained in the early stage or stages of the crushing, passing the clarified rich juice to the factory and mixing the rich mud therefrom with raw thin juice obtained in the late stage or stages of the crushing, defecating the mixture of rich mud and raw thin juice, passing the clarified thin juice to the evaporating plant and distributing the mud therefrom upon the megass at a point in the milling circuit where the liquid element of the mud is less rich in sugar than is the liquid content of the macerated megass which enters the rolls at the stage of crushing following next after the said distribution of mud upon the megass.

In testimony whereof we have signed our names to this specification in the presence of two subscribing witnesses.

NEHEMIAH MORTIMER THOMAS.
CUTHBERT GEORGE PETREE.
